TELEPHONE INSTRUMENT

Philip J. Thomas, Plantsville, and Leo F. Geremia, Wallingford, Conn., assignors to Connecticut Telephone and Electric Corporation, Meriden, Conn., a corporation of Delaware

Application May 23, 1951, Serial No. 227,886

6 Claims. (Cl. 179—100)

This invention relates to a structurally and functionally improved telephone instrument.

It is a primary object to furnish in a unit of this character a structure such that the parts may be adjusted and inspected without it being necessary to disconnect the instrument; the desired corrections and adjustments being capable of achievement without undesired signal and other impulses being transmitted to the line. Also, by means of the present teachings it will be feasible to utilize the instrument for either incoming or outgoing calls despite the fact that the parts have been opened for inspection and adjustment.

A further object is that of providing a telephone instrument in which positive snap-action type switches rather than leaf-type spring assemblies may be employed so that freedom from all difficulties in connection with the latter type switch is achieved.

With these and other objects in mind reference is had to the attached sheets of drawings illustrating one practical embodiment of the invention and in which:

Fig. 1 is a plan view of a telephone base;

Fig. 2 is a sectional side view taken along the line 2—2 and in the direction of the arrows as indicated in Fig. 1; Fig. 3 is a transverse sectional view taken along the line 3—3 and in the direction of the arrows as also indicated in Fig. 1;

Fig. 4 is a fragmentary sectional plan view; and,

Fig. 5 is a fragmentary view of a part of the assembly as shown in Fig. 3 but illustrating the mechanism in a different position.

In these views the reference numeral 10 indicates the base of the instrument which may be provided with supports 11. Accordingly, the assembly conveniently rests upon a surface such as a desk or table. However, by extending securing elements such as screws or bolts through the base the entire instrument may be supported upon a vertical surface such as a wall. A cover or casing 12 is normally secured against movement with respect to the base 10 by, for example, bolts 13. This cover is entirely removable from the base. As shown, it preferably includes a sloping front face 14 formed with an opening through which a dial 15 of any desired type is exposed; this dial conveniently extending substantially flush with the face of surface 14 when the cover is in mounted position. Surface 14 extends to one side of the assembly. A cradle portion extends to the other side of the center of that assembly and is preferably sloped in a direction opposite to that in which the surface 14 extends.

The cradle portion conveniently includes supporting surfaces 16 through which movable actuators 17 project. To each end of this surface fork portions are disposed. One of these fork portions may include a pair of pyramidal projections 18. The other embraces similarly surfaced projections 19 one of which is continued in the form of a ridge portion 20. Beyond each end of surface 16 the casing is relatively recessed as indicated at 21. That recess which is beyond or above the area of the dial is hollowed out or undercut as indicated at 22. Ridge portion 20 defines the outer edge of this socketed part or recess.

A hand set of conventional type is to be associated with this cradle portion. Such hand set embraces enlarged portions 23 and 24 at its opposite ends connected by an intermediate portion 25. The part 23 provides a housing for the ear piece or receiver unit. Recess 22 has its surfaces conformed so as to cooperate with and

support the surfaces of portion 23. At its opposite end the enlarged portion 24 of the hand set furnishes a housing for the transmitting unit of the telephone. As shown in dotted lines these several parts are supported by the 5 cradle portion whether the instrument be disposed upon a horizontal or vertical surface. Due to the sloping nature of the cradle surface it will be apparent that when the instrument is supported on a wall the receiver housing part will extend into the recess and the hand set will pivot so that its body presses against and retracts the plungers 17 extending upwardly beyond the cradle surface.

Obviously the same result will occur when the assembly is disposed upon a horizontal surface. In that case 15 the entire weight of the hand set will serve to maintain these plungers in retracted positions. It will also be apparent that in both positions the hand set will not be readily dislodged from its cradle support. Due to the 20 projections 18 and 19 as well as the contours of the upper or socketed recess, even if a person carelessly disposes the hand set in association with the cradle or parts adjacent thereto, the surfaces will function as cams to assure, under the action of gravity, that the hand set automatically reaches a properly mounted position. In that 25 position the intermediate portion 25 will bear against plungers 17 to project them inwardly.

The mechanism contained upon the base and within the casing has only been shown in somewhat diagrammatic manner. Also the circuit within which this mechanism is embraced has not been illustrated. Suffice it to say that in the latter it is preferably of a conventional nature and that the mechanism may also be conventional and include a capacitor, an induction coil and the usual assembly operated by the rotation of the dial. 35 However, contrary to conventional teachings, in lieu of employing a double pole, single throw switch of the customary leaf spring type, it is proposed to utilize snap-action type switches of the so-called "micro" class. These have been indicated as including casings 26 and 40 27 from which the conventional actuators 28 extend. They are conveniently mounted by a bracket 29 supported upon the base 10. Switch 26 controls the transmitter circuit and switch 27 controls the receiver circuit. Therefore, if these switches are closed in this sequence, 45 no induction pulse or connection occurs.

The dial 15 is mounted upon a bracket 30 with one end of which a securing bolt 31 may be associated. Accordingly, that end of the bracket may be fixed against movement with respect to the base 10 by having 50 the threads of the securing element 31 engage with the threads of a socketed portion secured to the base. The opposite end of the bracket is hingedly supported as at 32 upon a mounting 33 affixed to base 10. Also supported by pivot 32 is a fork member 34 the arms of which 55 underlie the plungers or actuators 17. Fork 34 may be provided with a central extension 35. A spring 36 is interposed between this extension and an extension 37 forming a part of bracket 30. Accordingly, under the influence of spring 36 the arms of fork 34 will yielding 60ly bear against the base portions of actuators 17 and tend to normally maintain them in an elevated position. The movement of fork 34 is conveniently limited by incorporating a stop in this structure. This may embrace a portion 38 integral with the fork and contactable with 65 the upper face of mounting 33.

Thus it is apparent that by loosening the securing element 31 bracket 30 may be swung from the position shown in full lines in Fig. 3 to that shown in dot-and-dash lines in that figure. In the former position when 70 actuators 17 are depressed they will cause fork member 34 to swing in a counterclockwise direction as viewed in Fig. 3 to the position shown in Fig. 5. Therefore, by means of the extension or spring 39 secured to move with the fork the switches 26 and 27 will be sequentially actuated. When bracket 30 is swung upwardly then projection 37 will swing downwardly. This will not alone relieve the tension on spring 36 to allow fork 34 to shift downwardly but will also (as in Fig. 5) result in projection 37 engaging the face of fork 34 to positively urge it downwardly. This will cause the strip 39 to sequentially engage actuators 28 of the switches and

shift them. In other words, the condition of these switches will be identical with that which they assume when the hand set is in position on the cradle and the cover mounted on the base. When the dial assembly is swung upwardly and the ends of the fork 34 moved downwardly, a stop or supporting strip 40 may limit the downward movement of the plungers or actuators 17.

It will be obvious that when the parts are in normal position then the instrument may be employed in a conventional manner. Should it be necessary to adjust the parts and especially the biasing spring associated with the ringer unit, ready access may be obtained to the mechanism. This is achieved by simply removing the cover 12 and then loosening the securing element 31 after which bracket 30 and the dial 15 are swung upwardly to the position shown in dot-and-dash lines in Fig. 3 substantially simultaneously with the removal of the hand set from the cradle portion. In such position both actuators 28 of switches 26 and 27 are depressed similarly to the manner in which they are retracted when the cover is mounted and the hand set is in position upon the cradle portion. Therefore, the operator at the switchboard will not be annoyed by undesired signal impulses. Also, the assembly is in a condition such that not only may incoming calls be received but also outgoing calls may be made. In either the latter instances it will of course be necessary to temporarily swing bracket 30 downwardly to a position at which the pressure on actuator 28 is relieved. With the bracket in raised position it is, of course, obvious that the technician will be able to obtain complete access to the assembly of apparatus mounted on the base.

Thus, among others, the several objects of the invention aforesaid are achieved. Obviously numerous changes in construction and rearrangement of the parts might be resorted to without departing from the spirit of the invention as defined by the claims.

We claim:

1. A telephone instrument including in combination a base, a dial movably mounted by said base to be shiftable towards and away from the same, a switch mounted by said base to control the operation of said instrument and governing means connected to shift with said dial to control the operation of said switch.

2. A telephone instrument including in combination a base, a dial movably mounted by said base to be shiftable towards and away from the same, a switch mounted by said base to control the operation of said instrument, a hand set cradle upon said base, an actuator extending beyond the surfaces of said cradle to be engaged by a hand set and connected to control the operation of said switch and governing means connected to shift with said dial to operate said switch.

3. A telephone instrument including in combination a base, a dial movably mounted by said base to be shiftable towards and away from the same, a switch mounted by said base to control the operation of said instrument, a hand set cradle upon said base, an actuator extending beyond the surfaces of said cradle to be engaged by a hand set and connected to control the operation of

said switch, the parts of said instrument being proportioned so that a removal of the hand set from said cradle is necessary at the time said dial is shifted, said actuator being therefore inoperative to control the operation of said switch and governing means connected to shift with said dial and upon the removal of said hand set to operate said switch.

4. A telephone instrument including in combination a base, a cover mounted upon said base and removable therefrom, said cover being formed with an opening, a dial unit disposed within said opening, a bracket hingedly mounted upon said base, said dial unit being supported by said bracket, a strip to overlie a circuit-controlling switch forming a part of said instrument for governing the operation of the latter and the means for connecting said strip with said bracket to move the former according to the movements of the latter.

5. A telephone instrument including in combination a base, a cover mounted upon said base and removable therefrom, said cover being formed with an opening, a dial unit disposed within said opening, a bracket hingedly mounted upon said base, said dial unit being supported by said bracket, a strip to overlie a circuit-controlling switch forming a part of said instrument for governing the operation of the latter, a member movably supported by said base and mounting said strip and means connecting said member and said bracket to shift the former and said strip responsive to the movements of said bracket.

6. A telephone instrument including in combination a base, a cover mounted upon said base and removable therefrom, said cover being formed with an opening, a dial unit disposed within said opening, a bracket hingedly mounted upon said base, said dial unit being supported by said bracket, a strip to overlie a circuit-controlling switch forming a part of said instrument for governing the operation of the latter, a member movably supported by said base and mounting said strip and means connecting said member and bracket to shift the former and said strip responsive to the movements of said bracket, a cradle portion forming a part of said cover, a movable actuator extending adjacent said cradle portion and means forming a part of said member to cooperate with said actuator and normally maintain it in projected position when said bracket is in a predetermined position.
